EGG CARTON SET-UP DEVICE

Martin Burger, Morris, Ill., assignor to General Package Corporation, a corporation of Delaware

Application May 23, 1950, Serial No. 163,608

18 Claims. (Cl. 93—37)

1

The present invention pertains to improvements in a manually operated device for setting up a particular style of flexible paperboard egg carton. The device is of the general type shown and described in the patent to Burger, Reissue No. 18,547 of July 26, 1932. The carton referred to is the subject of my copending application, Serial No. 135,804, filed December 29, 1949.

This carton is based, as regards its general features, on the principles of carton construction covered by the patent to Troyk No. 1,766,155 of June 24, 1930, and Troyk Reissue Patent No. 18,922 of August 22, 1933. Reference may be made thereto for a discussion of the general construction of the Troyk carton. It may be assumed that the carton dealt with by the subject set-up device is similar thereto in basic respects. It is further characterized by certain interlocking flaps and tabs on its respective cross and longitudinal partitions which it is the function of the present device to manipulate in timed relation to one another, concurrent with the manipulation of the partitions themselves, to bring the carton to erected condition.

It is a general object of the invention to provide an improved carton set-up device for performing all of the operations necessary to erect a special paperboard egg carton of the type generally described above.

A more specific object is to provide a carton set-up device of the sort referred to, characterized by a plurality of like sets of fixed abutments and swingable leaves which are adapted to engage and manipulate the swingable cross partitions of the carton to their proper positions at a right angle to the bottom and longitudinal partition forming panel of the carton; by a vertically oscillatable blade adapted to engage and shape the last named panel, shifting the same into proper, interengaged relation with the so positioned cross partitions; by a set of simultaneously reciprocable elements which are adapted to engage and manipulate certain integral tabs on the cross partitions in predeterminedly timed relation to the operation of the aforesaid leaves and blade, and to open the same at an angle to the cross partition for subsequent interlocking engagement with certain integral flaps on the longitudinal partition; and by a further set of knife elements carried by the aforesaid blade which are adapted to engage and deflect the longitudinal partition flaps to guide the same past and into final interlocked engagement with the cross partition tabs, in which device all of these operations are performed automatically in

2

a predetermined time sequence, requiring no further manual work on the part of the operators than that of properly positioning the carton relative to the device, of operating an actuating arm, and of removing the erected carton.

Yet a further object of the invention is to provide a device of the character outlined above which, with minor changes in design, is suited for the erection of the special carton described, in either a full dozen capacity, non-divisible embodiment of the latter, or in a divisible embodiment capable of being readily subdivided into two half-dozen capacity carton portions, said alternative adaptations of the device being basically similar with regard to the special functioning of the flap and tab interlocking provisions thereof.

The foregoing statements are indicative in a general way of the nature of the invention. Other and more specific objects will be apparent to those skilled in the art upon a full understanding of the construction and operation of the device.

Two embodiments of the invention are presented herein for purpose of illustration, but it will be appreciated that the invention may be embodied in other modified forms coming within the scope of the appended claims.

In the drawings,

Fig. 1 is a fragmentary plan view of the set-up device of the invention, in the embodiment thereof devised for the erection of non-divisible type cartons; this view being partially broken away and showing the various partition, flap and tab manipulating elements in an inoperative non-actuated position thereof;

Fig. 2 is a view in central longitudinal, vertical section through the bed of the device of Fig. 1, being taken along a line corresponding to line 2—2 of that figure;

Figs. 3 and 4 are fragmentary, generally similar figures in section corresponding to Fig. 2, showing the parts of the device in their operating relation to one another at successive later phases of the erecting operation, no carton being shown in position on the device in these figures in the interest of increased clarity;

Fig. 5 is a view in transverse vertical section through a fully erected carton of the type operated on by the present device, showing the erected and interlocked relationship of the cross and longitudinal partition tab and flap elements which results from the operation of the device;

Fig. 6 is a fragmentary perspective view of the

erected carton, still more clearly showing the relationships referred to;

Figs. 7, 8, 9 and 10 are similar and related somewhat schematic views in longitudinal vertical section through the device, illustrating the manner in which a partially squared carton blank is applied to the latter and manipulated thereby into fully erected interlocked condition;

Figs. 11, 12 and 13 are similar views in transverse vertical section along lines 11—11, 12—12 and 13—13 of Figs. 2, 3 and 4, respectively, further showing the operations and relationships of parts of the carton set-up device during successive stages of the erecting cycle; and

Fig. 14 is a view in longitudinal vertical section corresponding to the sectioning of Fig. 2, illustrating the device of the invention in a modified adaptation thereof for the erection of a divisible type carton.

Figs. 5 and 6, considered in conjunction with Figs. 7 through 13, adequately illustrate the paperboard egg carton C which is operated on by the device. It has a longitudinal partition, designated *a*, as an integral part of a bottom forming panel *b* of the blank from which the carton is constructed, which panel is shaped by the subject set-up device into an inverted V outline, in the completed form of the carton. The upper, longitudinal partition portion *a* thereof subdivides the interior of the carton into a pair of parallel rows. In the flat, knock-down condition of the carton, the cross partitions, designated *c*, are folded upon themselves about a medial crease *d* and are hinged to the front and rear side walls *e, f*, respectively, of the carton. They are adapted to be swung by the subject device into position normal to the bottom and longitudinal partition forming panel, whereby to penetrate and interengage with the bottom thereof when the same is thrust into the inverted V outline mentioned above. This subdivides the pair of rows into a plurality of cells, and the cross partitions interlock with the carton bottom to support it and the longitudinal partition in elevated position. A carton cover *g* is integrally hinged to rear wall *f*.

The particular carton C in question has tab elements *i* integrally formed on the cross partitions *c* thereof, the tab elements being hinged medially of their length on the cross partitions and being swingable so as to extend on opposite sides of the cross partitions and substantially at a right angle thereto, in the erected condition thereof. The longitudinal partition *a* has flaps *h* integrally formed thereon which are swung outwardly therefrom and interlocked in the vertical sense with the cross partition tabs *i*.

The operation of so interlocking the flaps and tabs involves the preliminary deflection thereof out of the respective panels in which they are disposed, plus continued control thereof until they are in final interengaged relation, manipulations which are practically impossible to perform without the aid of some sort of automatic equipment. This is due to the fact that the flaps and tabs of a number of similar cross and longitudinal partitions must be simultaneously shifted and predeterminedly engaged with one another in predetermined synchronization with the manipulation of the respective cross and longitudinal partitions themselves. Successful manual erection of such a special carton is obviously impossible, hence the present invention provides a simple, relatively inexpensive, manually operated device (though well adapted for automatic

operation, also) for performing the special manipulations necessary to shape the carton, operatively engage its cross and longitudinal partitions, and interlock their respective tabs and flaps. The device may be inexpensively produced for installation in any desired quantity in a commercial candling establishment, thereby enabling the advantages offered by the special carton to be put into use on a commercial scale.

Referring to the drawings, the operating instrumentalities of the subject set-up device are appropriately supported on an open cradle-like frame or bed 10 which is preferably fabricated from a one-piece casting for the sake of strength and rigidity, as well as economy of production cost. The bed includes a specially shaped right-hand end plate 11, as viewed in Figs. 1 through 4, a left-hand base cross piece 12, and a pair of parallel, longitudinally extending, front and rear side frame members 13, 14, respectively, these being integral with the members 11, 12. Frame members 13, 14 are specially shaped to act as pivotal supports, as will be described. An upright rear post 15 integral with the left-hand frame cross piece 12 inclines upwardly and somewhat rearwardly from the latter and a relatively heavy, longitudinally extending rear brace 16 integrally connects post 15 with the right-hand side plate 11. This rear brace is also integrally connected by a center strut 17 with the rear bed frame member 14, as illustrated in Fig. 2. The bed 10 is provided with outwardly extended, slotted supporting feet 10' for the purpose of bolting the device to a supporting table or other surface.

Right-hand end plate 11 has a thickened upper rear boss 18 integral therewith which is longitudinally aligned with a similar boss 19 on the rear left-hand post 15; these bosses are suitably bored to receive and journal a longitudinally extending main operating shaft 20. A thrust collar 21 is applied to the shaft immediately to one side of the right-hand boss 18 to serve as an end stop.

Plate 11 likewise has an integral, outwardly extending, forked bracket 22 formed thereon, which acts as a pivot for support of certain operating provisions to be described. Immediately forwardly of this bracket, an elongated, vertically extending guide slot 23 is formed in the plate, this slot being rounded and oppositely flared at its upper portion to guide and control a longitudinal partition shaping blade of the device, hereinafter referred to.

The front and rear longitudinal side frame members 13, 14 of the bed have integrally formed thereon a plurality of longitudinally spaced pairs of fixed upright abutments 25, the abutments of each pair being transversely aligned with one another and, in the main, being identical in shape, although oppositely oriented. The pairs of abutments are equally spaced longitudinally of the open bed or cradle of the device. It may be noted that the pair at the right-hand end of the bed, specially denoted 25', are shaped slightly differently from the remainder, in that each has recesses 46 formed therein for a purpose to be described, occasioned by the fact that certain carton cross partitions *c* on which they operate must be swung in the opposite direction from the rest of the partitions *c*.

A plurality of pivoted, cross partition manipulating leaves 27 are provided for coaction with the fixed bed abutments 25 in the operation of the device. These take the form of plate-like

elements of V-notched outline having side trunnions 28 extending from the lower margin thereof. The trunnions 28 are received in upwardly opening journal seats 29 of the bed side frames 13, 14; which seats are located adjacent and forwardly of the fixed abutments 25. Each of the leaves 27 is provided with a central, downwardly depending, forked arm 30 pivotally connected by a pin 31 with a longitudinally shiftable actuating bar 32 disposed beneath the series of leaves 27.

Actuating bar 32 is adapted to be engaged at its right-hand end by a short push rod 33 which is slidably mounted in the right-hand bed plate 11. This rod is in turn engaged at its outer end, externally of the plate 11, by a threadedly adjustable tappet 34 mounted on one end of an operating lever 35. Lever 35 is medially pivoted by a pin 36 in the forked bracket 22 on end plate 11; at its upper end it is provided with a cam follower member 37 which rides the specially shaped face cam 38. Cam 38 is carried on a rocker member 39 which is fixedly attached to the actuating shaft 28, a hand crank 40 being secured thereto. This enables a rocking motion through somewhat more than 90° to be imparted to cam rocker 39 and shaft 28 upon forward and downward swinging of the crank 40. As a result, lever 35 is shifted in clockwise direction, as viewed in Figs. 1 through 4, causing push rod 33 to be shifted to the left and accordingly shifting the actuating bar 32 a corresponding amount. A coiled tension spring 41 connecting one of the leaf forks 30 with the bed end plate 11 urges the actuating bar 32 and the series of leaves which are pivotally connected thereto in the opposite direction, i. e., toward the right in Fig. 1. Shifting of the bar 32 to the left thus produces simultaneous oscillation of the partition manipulating leaves 27, the upper V-notched plate portions thereof approaching the fixed bed abutments 25 to swing the cross partitions *c* to operative position normal to the carton walls *e*, *f* and bottom panel *b*.

Actuating bar 32 is provided with a plurality of sets of U-shaped deflecting members 42 which engage a pair of cross partition tabs *i* of each of the cross partitions to swing the same from the plane of the respective partitions. These members are appropriately fixed on the bar 32 in any desired fashion, as by being welded thereto or cast integral therewith. The members 42 include the laterally spaced, upwardly extending fingers 42' each of which terminates in a tab deflecting pin 43 (Fig. 3) extending to the left, as viewed in Figs. 1, 2 and 3, and adapted to engage a pair of cross partition tabs *i* when bar 32 travels to the left.

The number of such sets of members 42 is one less than the number of sets of partition swinging leaves 27, of which there are seven, since the provisions for deflecting the tabs *i* of the outermost right-hand cross partition of the carton are carried by the endmost partition manipulating leaf, specially designated 27'. These provisions take the form of a pair of pins 45 extending to the right from the right-hand surface of that leaf. The reason for the use of special deflecting means at this end of the device is that the end cross partition has its tab elements deflected in the opposite direction from the rest for interlock with the carton longitudinal partition of the latter. Referring to Fig. 3, it will be noted that the end bed abutments 25 are relieved or cut away somewhat on the inside

of the legs of its V shape, as indicated by reference numeral 46, to accommodate the special deflecting pins 45.

In addition to actuating the swingable leaves 27, 27' and the tab deflecting fingers 42' in the fashion described above, the hand crank 40 also controls operation of the bottom and longitudinal partition manipulating assembly, generally designated 47, by which the longitudinal partition of the carton is shaped and properly engaged with the cross partitions. This assembly includes a specially shaped arm 48 secured to the shaft 20 and, in the inoperative, retracted position of the same, projecting upwardly from the shaft. It is of relatively massive construction, being provided with an enlarged rear boss 49 which is rigidly pinned at 50 to the shaft 20. Arm 48 is curved forwardly at its outer end portion and terminates in a pair of longitudinally spaced bosses or shoulders 51 which are bored for the reception of a pivot pin 52 by which a bottom deflecting and manipulating blade 53 is hingedly articulated to arm 48. The blade has a loose swinging connection to the arm, limited in the degree of swing by coacting stops 50' on the arm and blade.

A coiled torsion spring 54 encircles shaft 20 to the left of the arm 48, being engaged at the outer end thereof to the upstanding bed post 19 and at the opposite end being lodged in one of a plurality of anchoring slots 55 formed in the adjacent surface of the arm boss 49. Spring 54 tends to urge the shaft 20 in a direction to retract the assembly 47 to its inoperative elevated position illustrated in Figs. 1, 2 and 11.

The bottom and longitudinal partition forming blade 53 has a guide lug 56 suitably secured thereto at the righthand end thereof. This lug projects outwardly to the right and is adapted to enter the vertical slot 23 of the bed end plate 11. As mentioned above, this slot is outwardly and upwardly flared to insure unfailing reception of the lug 56. Assurance is thus had that the pivoted blade 53 will follow a proper downward path in engaging and shaping the bottom and longitudinal partition forming panel *b* of the carton *C*.

Referring to Fig. 2, the blade 53 is provided with longitudinally spaced notches 58 along its outer, lower edge, for the purpose of straddling the cross partitions *c* of the carton as the blade moves downwardly. Each notch has associated therewith a further, flap deflecting, knife-like element 59, these elements projecting forwardly of the edge of the blade 53 and being adapted to engage the flaps *h* on the bottom and longitudinal partition panel *b* of the carton, thereby conditioning the flaps to wipe past the deflected interlocking tabs *i* on the cross partition and to subsequently interlock with the latter.

In the initial, flat knock-down condition of the carton, the longitudinal creased edge of longitudinal partition forming panel *b* constitutes an outer side margin thereof. The panel from which the cross partitions *c* are formed is folded upon itself and its medial, longitudinally extending, outer crease *d* overlies the cover panel *g*.

The operation of the device is shown in Figs. 7 to 13 inclusive. The body of the carton *C* is first manipulated in order to bring its front and rear walls *f*, *g* into open, generally rectangular outline, with bottom panel *b* and the panel containing cross partitions *c* extending therebetween in generally box-like outline. So expanded, the carton is inverted and applied to the device with the cover *g* thereof depending vertically along

the front of the device. The cross partitions *c* are engaged over and thrust down upon the rearwardly retracted leaves *27*, *27'* and fixed bed abutments *25*, *25'*, causing the partitions *c* to take the inclined position shown in Figs. 7 and 11. The handle *40* has not yet been actuated, the operation to this point being entirely preliminary in so far as the functioning of the device is concerned.

With the carton in place, as in Figs. 7 and 11, the handle *40* is grasped, while the operator steadies the carton body with his other hand, and swung forwardly and downwardly. The initial portion of the forward and downward stroke results in the swinging of the cross partition engaging leaves *27*, *27'* from the position of Fig. 7 to that of Fig. 8. This is accompanied by movement in the reverse direction of the tab deflecting pins *43*, due to their direct connection to the leaf actuating bar *32*, so that as the cross partitions *c* approach and reach the position shown in Fig. 8, the pairs of tabs *i* are engaged by the pins and pivoted about their respective medial hinges to a position at a right angle to the respective cross partitions. During these operations, the bottom and longitudinal partition shaping blade *53* is moving downwardly (see Fig. 12). However, it does not contact the bottom and longitudinal partition forming panel *b* of the carton *C* until after the cross partitions have been swung and the tabs deflected in the manner described.

The cross partitions *c* are now firmly gripped between the respective fixed abutments *25*, *25'* and leaves *27*, *27'*. At this point it should be noted that the pins *45* on the special leaves *27'* operate to deflect the tabs *i* at the right hand end of the carton in the opposite direction from the direction of deflection of the remaining tabs, as will be evident from an inspection of Fig. 3. As stated, the coacting fixed abutment *25'* is relieved somewhat at *46* to accommodate the pins *45* in their movement to the right. To the same end, the remaining cross partition swinging leaves *27* are recessed at *60* in the V-notched portion thereof (see Figs. 3 and 11-13) to provide clearance for the deflecting pins *43*, as well as to accommodate the swinging movement of the deflected tabs.

As the bottom shaping blade *53* continues to move downwardly, the knife-like flap deflecting elements *59* engage the pivoted flaps *h* on the longitudinal partition *a* and thrust the same downwardly and inwardly of the interior of the carton, as shown in Fig. 9. The purpose of this deflection of the flaps is to position them for sliding clearance past the previously deflected cross partition flaps *i*. The relative position of the parts at this phase is clearly illustrated in Fig. 9.

Further downward movement of the blade *53* by swinging of lever *40* now shifts the bottom and longitudinal partition panel inwardly and downwardly, by engagement of the edge of the blade *53* along the medial crease of panel *b*. The notches *58* of the blade straddle the cross partitions *c* during this movement and the latter are caused to be thrust into certain preformed slotted openings *j* in the bottom panel *b*, as shown in Figs. 9 and 13, whereby the integral, in-turned hook formations *k* on the cross partitions *c* are engaged with the inner extremity of these openings to lock the cross partitions and bottom and longitudinal partition forming panel in final position. Hooks *k* are thus interengaged with the carton bottom to sustain the same vertically.

As the foregoing operations take place, the de-

scending longitudinal partition flaps *h* brush past the tabs *i*, which are held in deflected position by pins *43* and come into final interlocked relation thereunder, as illustrated in Figs. 5, 6, 10 and 13.

5 The handle *40* of the device is allowed to return to original, inoperative position, the blade *53* to rise and the leaves *27*, *27'* to return to their original open condition. The completed, erected carton is then lifted off the bed of the device, in condition for filling with its intended contents.

The bottom of the carton is vertically sustained by the engagement of flaps and tabs *h*, *i*, respectively, as well as by the engagement of the cross partition hooks *j* in the slotted bottom openings *k*.

The adaptation of the invention described above and shown in Figs. 1 to 13 inclusive of the drawings is employed in the erection of cartons of full, non-divisible, 12-egg capacity. A 20 modified embodiment of the invention, designed to operate on cartons of the divisible type which are adapted to be separated along a central transverse weakened line into two carton sections of one-half dozen capacity, is illustrated 25 in Fig. 14. In this modification, many of the operating provisions, and in particular the supporting bed or frame, are practically identical in structure to those illustrated in Fig. 1 through 13; accordingly, corresponding reference numerals, primed, are applied thereto and further description is dispensed with.

In the form shown in Fig. 14 there are two like sets of fixed abutments *62* on bed *10'*, as well as two sets of coacting cross partition manipulating leaves *63* and reciprocating tab deflecting members *64*. The functions of these respective elements correspond to those of the abutments *25*, *25'*, leaves *27*, *27'* and deflecting members *42* of the first form. As regards the set of 35 these elements which is located to the left of the center of the device, the abutments *62* face outwardly or to the left and the leaves *63* swing clockwise or inwardly toward the same. These leaves have the actuating arm *65* thereof pivoted on a control bar *66* which extends the full length 40 of the device and is engaged at its right-hand end by the lever operated thrust rod *33'*. The tab deflecting elements *64* are mounted on bar *66* for travel to the left and engagement with the cross partition tabs *i*.

50 With regard to the set of abutments, leaves and deflecting members located to the right of the longitudinal center of the device, they are oriented and operate oppositely of the directions of orientation and operation of the left-hand set. The actuating arms *65* of the leaves are pivoted to a secondary actuating bar *67* which is received in a space *68* cut away from the lower portion of main control bar *66*. The bars *66* and *67* are oppositely movable relative to one another in the operation of the device.

The two swingable partition erecting leaves on immediate opposite sides of the center line of the device, specially designated *63'*, coact with an enlarged center abutment *69* on the bed *10'* 65 of the device, and these leaves have integral, oppositely facing tab deflecting pins *70* thereon which perform the function of the tab deflecting members *64*. Leaves *63'* are swingable oppositely toward one another in moving adjacent cross partitions *c* to operative position against abutment *69*, and in order to accomplish this movement each of the leaves *63'* has a segmental gear element *71* affixed to the trunnion thereof 70 outwardly of the rear side frame member *14*.

The gear segments 71 are in meshing engagement, whereby movement of the leaf 63 to the left of abutment 69, as the result of movement of the main control bar 66, results in equal, opposite swinging movement of the leaf 63' to the right of the abutment. The result is to swing the cross partitions *c* of the divisible type carton inwardly and upwardly toward and parallel to one another, clamping the same against the abutment 69. At the same time the cross partition tabs *i* thereof are deflected by the pins 70.

The bottom and longitudinal partition manipulating blade 71' shown in Fig. 14 is modified for coaction with the above described provisions in that the respective sets of notches 72 to the left and right of the longitudinal center are disposed oppositely, as are the flap deflecting knife elements 73 thereof. At the center line, the notches, specially denoted 72', are in close adjacency in view of the presence of two cross partitions in close adjacency at this zone. The same is true of knife elements 73'.

It is believed that extended description of the operation of the device according to the embodiment of Fig. 14 is uncalled for. It simply represents an extension of the principles underlying the structure of Figs. 1 through 13 to accomplish the erection of a still further specialized type of carton.

The device is inexpensive in character, readily operated by comparatively unskilled personnel. It successfully performs the relatively complicated operations of erecting the disclosed carton with complete reliability. It can be readily and quickly installed in an egg room in any desired number, depending upon the production requirements or output of the egg room in question.

I claim:

1. Apparatus for erecting partition-type egg cartons, comprising members adapted to engage and actuate the cross partitions of a carton from a position generally paralleling the wall and bottom panels thereof to a position transverse of said panels, means to deflect certain locking tabs of said cross partitions from a position in the plane thereof to an angular relation thereto, and means to operate said members and tab deflecting means in timed relation to one another.

2. Apparatus for erecting partition-type egg cartons, comprising a set of members adapted to engage and actuate the cross partitions of a carton from a position generally paralleling the wall and bottom panels thereof to a position transverse of said panels, a set of members operative to deflect certain locking tabs of said cross partitions from a position in the plane thereof to an angular relation thereto, and means to operate said sets in timed relation to one another, including means interposed between and connected to said respective sets to operate one thereof in response to actuation of the other.

3. Apparatus for erecting partition-type egg cartons, comprising members adapted to engage and actuate the cross partitions of a carton from a position generally paralleling the wall and bottom panels thereof to a position transverse of said panels, means operative during said actuation to deflect certain locking tabs of said cross partitions from a position in the plane thereof to an angular relation thereto, means to engage the bottom panel with said cross partitions, means to deflect certain flaps in said bottom panel to an angular relation thereto, and means to operate said members, panel engaging means and tab and flap deflecting means in timed relation

to one another to interengage said tabs and flaps in the erected condition of the carton.

4. Apparatus for erecting partition-type egg cartons, comprising a base, sets of relatively movable members on said base adapted to engage and actuate the cross partitions of a carton from a position generally paralleling the wall and bottom panels thereof to a position transverse of said panels, a blade movable relative to said base for engagement with the bottom panel of the carton to shape and engage the same in erected relation to said cross partitions, means on said blade to deflect certain flaps in said bottom panel to an angular relation thereto, and means to operate said members, blade and flap deflecting means in timed relation to interengage said cross partitions and flaps in the erected condition of the carton, said operating means comprising an operating member on which said blade is loosely pivoted and an actuating connection between said operating member and said sets of relatively movable members on said base, said base being provided with guide means to engage and control said blade in the bottom shaping movement thereof.

5. Apparatus for erecting partition-type egg cartons, comprising a base, sets of relatively movable members on said base adapted to engage and actuate the cross partitions of a carton from a position generally paralleling the wall and bottom panels thereof to a position transverse of said panels, means to deflect certain locking tabs of said cross partitions from a position in the plane thereof to an angular relation thereto, a blade movable relative to said base for engagement with the bottom panel of the carton to shape and engage the same in erected relation to said cross partitions, means on said blade to deflect certain flaps in said bottom panel to an angular relation thereto, and means to operate said members, blade and tab and flap deflecting means in timed relation to interengage said tabs and flaps in the erected condition of the carton, said operating means comprising an operating member on which said blade is loosely pivoted and an actuating connection between said operating member and said sets of relatively movable members on said base, said base being provided with guide means to engage and control said blade in the bottom shaping movement thereof.

6. Apparatus for erecting partition-type egg cartons, comprising pairs of relatively movable members adapted to engage and actuate the cross partitions of a collapsed carton from a position generally paralleling the wall and bottom panels thereof to a position transverse of said panels, means to deflect certain locking tabs of said cross partitions from a position in the plane thereof to an angular relation thereto, an element engageable with the bottom panel of the carton to shape and engage the same in erected relation to said cross partitions, means carried by said element to deflect certain flaps in said bottom panel to an angular relation thereto, and means to operate said members, element and tab and flap deflecting means in timed relation to one another to interengage said tabs and flaps in an erected condition of the carton.

7. Apparatus for erecting partition-type egg cartons, comprising a set of pairs of relatively movable members adapted to engage and actuate the cross partitions of a collapsed carton from a position generally paralleling the wall and bottom panels thereof to a position transverse of said panels, a set of members operative to deflect cer-

11

tain locking tabs of said cross partitions from a position in the plane thereof to an angular relation thereto, an element engageable with the bottom panel of the carton to shape and engage the same in erected relation to said cross partitions, means carried by said element and operative during said shaping to deflect certain flaps in said bottom panel to an angular relation thereto, and means to operate said sets of members and said element in timed relation to one another to interengage said tabs and flaps in an erected condition of the carton, including means interposed between and connected to said respective sets to operate one thereof in response to actuation of the other, and means operatively connecting said element to one of said sets.

8. Apparatus for erecting a collapsed paper-board egg carton, comprising sets of coacting, relatively movable members adapted to engage and position certain cross partitions of the carton in a predetermined transverse angular relation to the walls and bottom thereof, means to engage and deflect certain tabs of said cross partitions to an angular relation thereto, said last named means being operatively connected to said partition positioning members to deflect said tabs substantially coincident with the positioning of said cross partitions, and means operating in timed relationship to said partition positioning members to position said bottom in interlocked relation to said cross partition tabs.

9. Apparatus for erecting a collapsed paper-board egg carton, comprising sets of coacting, fixed and relatively movable members adapted to engage and position certain cross partitions of the carton in a predetermined transverse angular relation to the walls and bottom thereof, means acting in opposition to said relatively movable members to engage and deflect certain tabs of said cross partitions to an angular relation thereto, said last named means being operatively connected to said movable partition positioning members to deflect said tabs substantially coincident with the positioning of said cross partitions, and means operating in timed relationship to said movable partition positioning members to position said bottom in interlocked relation to said cross partition tabs.

10. Apparatus for erecting a collapsed paper-board egg carton, comprising sets of coacting, fixed and oscillatable members adapted to position certain cross partitions of the carton in a predetermined transverse angular relation to the walls and bottom thereof, means reciprocable in opposition to said oscillatable members to deflect certain tabs of said cross partitions to an angular relation thereto, said last named means being operatively connected to said oscillatable partition positioning members to deflect said tabs substantially coincident with the positioning of said cross partitions, and means operating in timed relationship to said partition positioning members to engage and shape said bottom and to position the latter in interlocked relation to said cross partitions and tabs.

11. Apparatus for erecting a collapsed paper-board egg carton, comprising sets of coacting, fixed and oscillatable members adapted to position certain cross partitions of the carton in a predetermined transverse angular relation to the walls and bottom thereof, means reciprocable in opposition to said oscillatable members to deflect certain tabs of said cross partitions to an angular relation thereto, said last named means being operatively connected to said oscillatable

12

partition positioning members to deflect said tabs substantially coincident with the positioning of said cross partitions, and means operating in timed relationship to said partition positioning members to engage and shape said bottom and to position the latter in interlocked relation to said cross partitions and tabs, said last named means including a bottom engaging blade and elements on said blade engageable with certain flaps on said bottom to position the same for interlocking with said cross partition tabs.

12. In a carton set-up apparatus, means to position certain cross partitions of a collapsed carton in erected transverse relation to the walls and bottom thereof, including means to deflect certain cross partition tabs to an angular relation to the respective cross partitions, means to engage said bottom with said positioned cross partitions, including means to deflect certain flaps on said bottom to an angular relation thereto, and means to actuate said respective means in timed relation to cause said deflected tabs and flaps to have wiping contact with one another in approaching and assuming an operatively interlocked relation coincident with the positioning of said cross partitions and bottom in engaged relation to one another.

13. Carton set-up apparatus, comprising a support, coacting relatively movable members on said support adapted to position certain cross partitions of a carton in erected transverse relation to the walls and bottom thereof, a blade movable relative to said support and members to engage said bottom with said positioned cross partitions, a set of fingers simultaneously movable on said support relative to said members to engage and deflect certain cross partition tabs to an angular relation to the respective cross partitions positioned by said members, elements on said blade adapted during the operation of the latter to engage and deflect certain flaps on said bottom to an angular relation thereto, and means to actuate said set of fingers, said members and said blade in timed relation to one another whereby said tabs and flaps have wiping contact with one another in the positioning of said cross partitions and bottom in engaged relation to one another and the tabs and flaps in interlocked engagement.

14. Carton set-up apparatus, comprising a support, coacting relatively movable members on said support adapted to position certain cross partitions of a carton in erected transverse relation to the walls and bottom thereof, a blade movable relative to said support and members to engage said bottom with said positioned cross partitions, a set of fingers simultaneously movable on said support relative to said members to engage and deflect certain cross partition tabs to an angular relation to the respective cross partitions positioned by said members, elements on said blade adapted during the operation of the latter to engage and deflect certain flaps on said bottom to an angular relation thereto, and means to actuate said set of fingers, said members and said blade in timed relation to one another whereby said tabs and flaps have wiping contact with one another in the positioning of said cross partitions and bottom in engaged relation to one another and the tabs and flaps in interlocked engagement, said relatively movable partition positioning members being arranged in sets on opposite sides of the midpoint of said support, which sets are reversed with regard to the direction of relative movement of the members thereof.

15. Carton erecting apparatus of the type described, comprising a support, two cross partition engaging units mounted oppositely on said support, each unit including a plurality of pairs of relatively oscillatable cross partition engaging members adapted to position the cross partitions of a carton in operative angular relation to the carton walls and bottom, means to deflect certain tabs from the respective planes of said cross partitions, including two sets of deflecting elements mounted for opposite reciprocating movement relative to said members of said respective units, means operatively connecting said positioning members and deflecting elements for simultaneous movement of said respective members relative to one another and of said elements relative to said members, a bottom shaping plate movable relative to said members and elements, and common operating means for said plate, members and elements adapted to move the same in timed relation to one another.

16. Carton erecting apparatus of the type described, comprising a support, a plurality of pairs of relatively oscillatable cross partition engaging members on said support adapted to position the cross partitions of a divisible type carton in operative angular relation to the carton walls and bottom, said pairs being arranged in sets on opposite sides of the longitudinal midpoint of said support and being oppositely oriented in said respective sets, means to deflect certain tabs from the respective planes of said cross partitions, including two sets of deflecting elements mounted on opposite sides of the midpoint of said support for opposite reciprocating movement relative to one another and to said members, means operatively connecting said positioning members and deflecting elements for simultaneous movement

of said respective members relative to one another and of said elements relative to said members, a bottom shaping plate movable relative to said members and elements, and common operating means for said plate, members and elements adapted to move the same in timed relation to one another.

17. Apparatus for erecting partition-type cartons, comprising a frame having members thereon adapted to engage and actuate the cross partitions of a carton from a position generally paralleling the wall and bottom panel thereof to a position transverse of said panels and frame, further elements movably mounted on said frame and acting to deflect certain locking tabs of said cross partitions from a position in the plane thereof to an angular relation thereto, means to actuate said elements longitudinally of said frame into engagement with said tabs of certain of said transversely disposed cross partitions, and means to engage and interlock said tabs with said bottom panel.

18. Apparatus in accordance with claim 17 in which said members include members movably mounted on said frame and elements thereon engageable with the locking tabs of other of said cross partitions to deflect the same from coplanar relation to the plane of the cross partition to an angular relation thereto.

MARTIN BURGER.
